UNITED STATES PATENT OFFICE.

JAMES GRAHAM GREEN, OF COLORADO SPRINGS, COLORADO.

GLASS-CUTTING TABLE.

No. 802,633.

Specification of Letters Patent.

Patented Oct. 24, 1905.

Application filed June 1, 1905. Serial No. 263,318.

To all whom it may concern:

Be it known that I, JAMES GRAHAM GREEN, a citizen of the United States, residing at Colorado Springs, in the county of El Paso and State of Colorado, have invented a new and useful Glass-Cutting Table, of which the following is a specification.

This invention relates to an improved attachment for glaziers' tables, and has for its object to provide a simple, inexpensive, and efficient device of this character capable of being readily attached to glass-cutting tables or boards in general use and by means of which an unskilled person may conveniently and accurately cut either plane or plate glass in any desired angular shape.

A further object of the invention is to provide means whereby the rule or straight-edge may be adjusted longitudinally of the table to cut pieces of glass of different widths and means for securely clamping said straight-edge in adjusted position.

A further object is to provide means for yieldably supporting the rule or straight-edge carrying-bar, whereby the same may be adjusted vertically to accommodate glass of different thicknesses.

A still further object of the invention is to provide means for automatically elevating the rule or straight-edge after each cutting operation, so as to permit a new pane of glass to be placed in position on the board or table.

With these and other objects in view the invention consists in the construction and novel combination and arrangement of parts hereinafter fully described, illustrated in the accompanying drawings, and pointed out in the claims hereto appended, it being understood that various changes in form, proportions, and minor details of construction may be resorted to without departing from the principle or sacrificing any of the advantages of this invention.

In the accompanying drawings, forming a part of this specification, Figure 1 is a top plan view of a glazier's board or table constructed in accordance with my invention. Fig. 2 is a side elevation of a portion of the same, showing the straight-edge in elevated position. Fig. 3 is a side elevation, partly in section, of the clamping members of the straight-edge. Fig. 4 is a vertical sectional view of one of the corner castings or brackets. Fig. 5 is a vertical sectional view taken on the line 5 5 of Fig. 4. Fig. 6 is a transverse sectional view taken on the line 6 6 of

Fig. 5, and Fig. 7 is a detail sectional view of the locking-lever.

Similar numerals of reference indicate corresponding parts in all the figures of the drawings.

The cutting board or table 5, which may be of the usual shape and formed of wood, metal, or other suitable material, is provided at the rear thereof with corner brackets or castings 6, in which is journaled a graduated guide bar or rod 7, the latter being preferably angular in cross-section and provided with terminal trunnions 8, which engage elongated slots or openings 9, bored, cast, or otherwise formed in the vertical extensions 10 of said brackets, as shown. The brackets 6 are provided with integral laterally-extending wings 11, which engage suitable recesses 12 in the face of the board, so as to present a smooth even surface to the glass to be cut and also to form an additional means for securing said brackets to the table or board. The bar 7 is preferably graduated to inches and fractions thereof, as shown, and slidably mounted on said bar is a rule or straight-edge 13, also preferably graduated to inches and fractions thereof, so that the operator can determine at a glance the exact length and width of the glass to be cut without resorting to the use of auxiliary rules and similar measuring devices.

Carried by one end of the rule or straight-edge is a clamping member preferably formed in two sections 14 and 15, the section 14 being riveted or otherwise rigidly secured to the rule, as indicated at 16, while the section 15 is pivoted or hinged thereto, as shown at 18, whereby when the clamp is operated the angular sockets 19 of the clamp-sections 14 and 15 will engage the bar 7 and effectually retain the rule or straight-edge in adjusted position. The clamping member is operated to engage the bar 7 by means of a hand-lever 20, pivoted between a pair of spaced lugs 21 at a point adjacent the free end of the rule or straight-edge, and to which is fastened in any suitable manner one end of a flexible rod or wire 22, the opposite end of which passes through suitable guiding loops or eyes 23 and is secured to a vertically-disposed arm or lug 24, preferably formed integral with the movable clamping-section and extending through an opening 25 in the adjacent fixed section, as shown. The flexible rod or wire also passes through a terminal opening in a lever 26, which latter is pivoted between a pair of vertical ears 27 on the clamping-section 14 and

is provided with a curved lug or extension 28, adapted to bear against the clamping-section 14 when a longitudinal pull is exerted on the wire 22. It will thus be seen that when the 5 hand-lever is moved to the position shown in Fig. 2 of the drawings the movable section will be elevated to thereby clamp the rod or bar 7, in which position it will be securely locked until said hand-lever is released.

10 As a means for automatically elevating the rule or straight-edge after each cutting operation suitable coil-springs 28' are provided, the normal tendency of which is to rotate the bar 7 in the direction of the arrow shown in 15 Fig. 4, whereby when the clamping member is released and the hand removed from the free end of the straight-edge the latter will automatically assume the vertical position shown in Fig. 2 of the drawings, thereby permitting 20 a new pane of glass to be properly positioned on the board or table. The springs 28' are seated in suitable openings 29, formed in the corner-brackets 6, and are secured, respectively, to the trunnions 8 of the bar 7 and 25 the interior walls of said openings, as shown. In order to adapt the device for cutting glass of different thicknesses, the bar 7 is also preferably yieldably supported in the slots 9, so as to afford the same a limited vertical 30 movement, suitable springs 30, disposed in recesses 31 in the brackets and bearing upon the trunnions 8, serving to normally hold the bar depressed. It will thus be seen that the 35 bar 7 is capable of both rotary and vertical movement and that the straight-edge being carried by said bar will also be elevated with the latter.

The corner-brackets 6 are preferably provided with detachable caps 32, so that the 40 latter may be conveniently removed to facilitate the introduction and removal of the spring.

Secured to one end of the bar 7 is a depending bracket or stop 33, the free end of which 45 is adapted to engage the rear edge of the table 5 to thereby limit the upward movement of the straight-edge when the latter is released, so that said straight-edge may be supported within easy reach of the operator.

50 From the foregoing description it is thought that the construction and operation of the device will be readily understood, and further description thereof is deemed unnecessary.

Having thus described the invention, what 55 is claimed is—

1. The combination with a board or table, of a guiding member carried by the table, a straight-edge slidably mounted on the guiding member and movable to operative position 60 substantially parallel with the table, and means for automatically elevating the free end of the straight-edge when the latter is released.

2. The combination with a board or table, of a guiding member secured to one side of 65 the table, a straight-edge slidably mounted on

the guiding member and movable to operative position substantially parallel with the table, and means for normally supporting the free end of said straight-edge in elevated position, said means serving to automatically return 70 the straight-edge to inoperative position when the latter is released.

3. The combination with a board or table, of a guiding member carried by the table, a straight-edge slidably mounted on the guiding member and adapted to travel over the surface of the table, means for normally supporting the free end of said straight-edge in elevated position, means for clamping the latter to the guiding member, and means for 80 limiting the upward movement of the straight-edge. 75

4. The combination with a board or table, of a guiding member secured to one side of the table, a straight-edge carried by the guiding 85 member and adapted to travel over the surface of the table, and means for yieldably supporting the free end of said straight-edge in elevated position, and means carried by the guiding member for limiting the upward 90 movement of the straight-edge.

5. The combination with a board or table, of a vertically-adjustable guiding member carried by the table, a straight-edge mounted on the guiding member and adapted to travel 95 over the surface of the table, and means for normally supporting the free end of said straight-edge in elevated position.

6. The combination with a board or table, of a guiding member yieldably supported for 100 vertical movement at one side of the table, a straight-edge slidably mounted on the guiding member and adapted to travel over the surface of the table, and means for normally supporting the free end of said straight-edge 105 in elevated position.

7. The combination with a board or table, of a guiding member secured to one side of the table, a straight-edge slidably mounted on the guiding member and adapted to travel 110 over the surface of the table, and a spring carried by the guiding member for normally supporting the free end of said straight-edge in elevated position.

8. The combination with a board or table, 115 of a guiding member secured to one side of the table and mounted for vertical and rotary movement, a straight-edge slidably mounted on the guiding member and adapted to travel over the surface of the table, and means carried by the guiding member for yieldably supporting said straight-edge in elevated position.

9. The combination with a board or table, 125 of a guiding member supported at one side of the table, a straight-edge slidably mounted on the guiding member and movable to operative position substantially parallel with the surface of the table, means for clamping the straight-edge in adjusted position on the guid- 130

ing member, and means for automatically elevating the free end of said straight-edge when the latter is released.

10. The combination with a board or table, of a guiding member supported on one side of the table, a straight-edge adapted to travel over the surface of the table and provided with a terminal clamp adapted to engage said guiding member, means carried by the straight-edge for operating said clamping member, and means for automatically elevating the free end of said straight-edge when the clamping member is released.

11. The combination with a board or table, of supporting-brackets secured to one side thereof, a guide-rod journaled in said brackets, a straight-edge slidably mounted on the guide-rod and movable to operative position substantially parallel with the surface of the table, and means for automatically elevating the free end of said straight-edge when the latter is released.

12. The combination with a board or table, of supporting-brackets secured to one side thereof and provided with aligned vertical slots, a vertically-adjustable guiding-rod journaled in the slots of the brackets, a straight-edge slidably mounted on the guide-rod and adapted to travel over the surface of the table, yieldable means for normally depressing the guide-rod, and means carried by said rod for normally supporting the free end of said straight-edge in elevated position.

13. The combination with a board or table, of supporting-brackets secured to one side thereof and provided with aligned vertical slots having recesses communicating therewith, a vertically-adjustable guide-rod journaled in the slots of said brackets, a straight-edge slidably mounted on said guide-rod and movable over the surface of the table, springs seated in said recesses and bearing upon the guide-rod for normally depressing the latter, and a spring secured to each end of said rod for normally elevating the free end of said straight-edge.

14. The combination with a board or table, of a graduated guiding member secured to one

side of the table, a graduated straight-edge slidably mounted on the guiding member and adapted to travel over the surface of the table, a clamping member carried by the straight-edge for engagement with said guiding member, and means carried by the straight-edge for operating said clamping member.

15. The combination with a board or table, of a guide-rod supported at one side of the table, a straight-edge slidably mounted on the rod and adapted to travel over the surface of the table, a fixed and a movable clamping member carried by the straight-edge for engagement with the rod, a lug secured to the movable member and passing through a slot in the fixed member, an arm pivoted to the fixed member in advance of said lug, an operating-lever carried by the free end of the straight-edge, and a flexible connection between the lug, arm and operating-lever.

16. The combination with a board or table, of a guiding member secured to one side of the table, and mounted for vertical and rotary movement, a straight-edge carried by the guiding member and adapted to travel over the surface of the table, means for yieldably supporting the free end of said straight-edge in elevated position, and means for limiting the upward movement of the same.

17. The combination with a board or table, of supporting-brackets secured to one side thereof, a guide-rod journaled in said bracket, a straight-edge slidably mounted on the guide-rod and adapted to travel over the surface of the table, means for normally supporting the free end of the straight-edge in elevated position, and a depending stop carried by the guide-rod and adapted to engage the table for limiting the upward movement of said straight-edge.

In testimony that I claim the foregoing as my own I have hereto affixed my signature in the presence of two witnesses.

JAMES GRAHAM GREEN.
